(57) **CLAIM**

The ornamental design for a reader antenna assembly, as shown and described.

DESCRIPTION

FIG. 1 is an oblique view of a reader antenna assembly, taken from the front and left side, showing our new design; FIG. 2 is a front elevation view thereof; FIG. 3 is a right side elevation view thereof, FIG. 4 is a left side elevation view thereof, FIG. 5 is a top plan view thereof, FIG. 6 is a bottom view thereof, FIG. 7 is a rear elevation view thereof; and, FIG. 8 is another oblique view thereof, exploded. The broken lines represent portions of the reader antenna assembly that form no part of the claimed design.
